UNITED STATES PATENT OFFICE.

CHARLES ROUSE AND NORWELL C. NEEMES, OF PITTSBURG, PENNSYLVANIA.

COKE-PUSHING MACHINE.

No. 803,783.

Specification of Letters Patent.

Patented Nov. 10, 1908.

Application filed April 20, 1908. Serial No. 428,982.

To all whom it may concern:

Be it known that we, CHARLES ROUSE and NORWELL C. NEEMES, citizens of the United States of America, residing at Pittsburg, in 5 the county of Allegheny and State of Pennsylvania, have invented certain new and useful Improvements in Coke-Pushing Machines, of which the following is a specification, reference being had therein to the 10 accompanying drawing.

This invention relates to a coke pushing machine particularly designed for that class of retorts which are employed in the production of coke and technically known as coke 15 ovens.

The primary object of our invention is to provide a coke pushing machine that can be advantageously used in connection with the oblong type of oven, the machine being compact whereby it will occupy, when not in use, a less area than the oven.

A further object of this invention is to provide a coke pushing machine that can be successfully manipulated between two rows 25 of ovens, appropriate mechanism being employed for moving the machine, whereby the ovens of a large plant can be operated upon in succession.

The invention in its broadest aspect involves positive and reliable means for operating a telescopic pusher in an undulatory manner, while coke is being removed from an oven.

To this end we have devised a machine 35 embodying a plurality of structural elements which when combined provide a safe, durable and easily manipulated machine.

The principal elements of the invention—namely, a carriage, a revoluble frame, a telescopic pusher, and the operating mechanism—will be hereinafter separately and 40 specifically described in detail, together with the novel arrangement and objects accomplished from such a combination of elements.

The preferred embodiments of our invention are illustrated in the accompanying drawings; but we desire it to be understood that the same are susceptible to various 50 changes without departing from the scope of the invention.

Reference now being had to the drawings;—Figure 1 is a side elevation of our machine, Fig. 2 is a plan of the same, Fig. 3 55 is a front elevation of the machine, Fig. 4 is a rear elevation of the same, Fig. 5 is a plan

of the carriage forming part of the machine. Fig. 6 is a longitudinal sectional view of the telescopic pusher. Fig. 7 is a horizontal sectional view of the same. Fig. 8 is a horizontal sectional view of the machine illustrating the telescopic pusher and the revoluble frame in plan, and Fig. 9 is a diagrammatic view of our machine. Fig. 10 is a cross sectional view of the telescopic 65 pusher.

Our coke pushing machine in its entirety is constructed of strong and durable metal consisting of castings, angle-bars, braces and frames, which are assembled to provide 70 a rigid non-frictional equi-balanced machine. In connection with the machine, we employ a telescopic pusher approximately twice the length of the machine, this pusher being adapted to enter an oven and push 75 the contents thereof out of the oven, at the opposite side of the oven from which the pusher enters. The stability of the machine permits of the pusher being steadily operated without breaking or disintegrating the coke 80 within an oven, and the construction of the pusher is such that coke dust or similar particles of coke will not interfere with the telescopic feature of the pusher.

The operating mechanism is assembled at 85 a central point upon the machine, whereby the machine can be easily and quickly manipulated by one operator.

Considering the various features of the invention in detail, reference will first be had 90 to the carriage.

The carriage.—The carriage consists of an oblong metallic frame 1 provided with transverse girders 2, 3, 4 and 5 connected by diagonally disposed braces 6. Journaled 95 longitudinally of the frame 1 and extending through the girders 2 is a shaft 7, said shaft being composed of a plurality of sections coupled together, as at 8, whereby the shaft can be easily placed in the frame after the 100 same has been erected. The shaft 7 between the girders 2 is provided with flanged wheels 9, and other flanged wheels 10 are journaled between the girders 2 whereby the carriage can travel upon the rails 11 provided therefor, said rails constituting a track located in front of the coke ovens. The shaft 7 is provided with a gear wheel 12 meshing with a gear wheel 13 mounted upon the armature shaft of a motor 14, said 110 motor being suspended within the frame between the girders 5. Riveted or otherwise

secured to the girders 4 is a circular rack 15 having a central bearing 16 and a pin 17. The ends of the frame 1 are provided with curved tread plates or rails 18, the object of 5 which will presently appear.

In order that the carriage can be moved upon the rails 11, we arrange a suitable trolley 19 (see Fig. 1) at one side of the track, this trolley supplying the electrical energy 10 to the motor 14 and other motors to be hereinafter described.

The revoluble frame.—The revoluble frame consists of side rails 20 connected by transverse girders 21 and diagonally disposed braces 22. The side rails 20 are provided with uprights 23 for a superimposed structure comprising a platform 24. The bottom of the frame is provided with a circular bearing plate 25 to receive the bearing 20 pin 17 of the circular rack 15. The bearing plate 25 is provided with suitable anti-friction bearings, preferably rollers 26, while the ends of the revoluble frame are provided with rollers 27 adapted to travel upon the 25 tread plates or rails 18. The rear end of the frame is provided with vertical bearings 28 for three sheaves 29, 30 and 31. We reserve the right to use ball bearings in lieu of the rollers 26.

30 *The telescopic pusher.*—The telescopic pusher consists of an outer member and an inner member, these members being approximately the length of the machine and are substantially rectangular in cross section. 35 The outer member comprises flanged side plates 32 connected by a top plate 33. The forward end of the member is provided with a pusher head 34 reinforced, as at 35 and braced as at 36. The outer member is provided with uprights 37 connected by transverse angle bars 38 supporting upon their outer ends shoes 39, these shoes supporting the forward end of the outer member upon the revoluble frame, while the rear end of 45 the outer member is supported by the rear end of the inner member. The inner member comprises flanged side plates 40 and a top plate 41. The inner sides of the plates 32 of the outer member are provided with 50 wheels 42 adapted to travel upon the flanges 43 of the plates 40. The rear end of the inner member is provided with a cross head 44, the ends of which are provided with flanged wheels 45 adapted to travel upon the 55 side rails 20 of the revoluble frame. The cross head 44 intermediate its ends is provided with a bearing 46 for two shafts 47 and 48, upon which are journaled sheaves 49 and 50. The rear end of the outer member is provided with a transverse plate 51 supporting the bearing 52 for a shaft 53 upon which is revolubly mounted a sheave 54. The forward end of the inner member is provided with a shaft 55 for a revoluble 60 sheave 56. The forward end of the revolu-

ble frame is provided with a revoluble sheave 57 and with a transverse stop 58 adapted to limit the forward movement of the cross head 44 and the inner member by contacting with the bearing 46. Adapted to 70 travel over the sheaves previously mentioned are cables which will be presently described.

The operating mechanism.—Upon the platform 24 is located an electric motor 59 and coupled to the armature shaft of said 75 motor as at 60 is a worm 61 meshing with a gear wheel 62 mounted upon a vertical shaft 63, journaled in a bearing 64 supported from the platform 24. The lower end of the shaft 63 extends through a suitable bearing 65 80 carried by the revoluble frame and is provided with a pinion 66 meshing with the circular rack 15. The operation of the motor 59 is controlled by a conventional controller 67 located upon the platform 24. 85 The platform 24 is provided with an opening 68 and surrounding this opening is a rectangular bearing or frame 69 for supporting revoluble drums 70 and 71, these drums being operated simultaneously by a 90 train of gears 72 driven by an electric motor 73, the operation of which is controlled by another controller 74, located upon the platform 24 adjacent to the controller 67. Another controller 75 is placed upon the platform 24 for controlling the operation of the motor 14 of the carriage 1. The platform 24 is provided with hangers 76 for revoluble sheaves 77 and 78. Attached to the drum 71 is a cable 81, said cable passing under the 95 sheave 78, through the cross head 44, over the sheave 29, under the sheave 49, around the sheave 54 and fastened to the revoluble frame, as at 80. This arrangement of the cable is best shown in Fig. 9, wherein the 100 arrangement of the cables is diagrammatically illustrated. Another cable 79 is fastened to the drum 70, this cable passing under the sheave 77, through the cross head 44, over sheave 30, down under the sheave 31, 110 along the revoluble frame to the sheave 57, and around same back through the revoluble frame to the sheave 50, up over the sheave 49, forward through the inner member of the telescopic pusher to the sheave 56, 115 over said sheave and rearwardly to the bearing 52 of the outer member, where it is secured as at 82.

General operation.—Assuming that our coke pushing machine has been pushed in 120 front of a coke oven and the door thereof opened, the operator of the machine located upon the platform 24 at the controllers 67, 74 and 75 manipulates the controller 74 to place the motor 73 in operation in the direction to wind the cable 79 upon the drum 70 and unwind the cable 81 from the drum 71, it being understood that these cables are of a sufficient length to permit of the drums 70 and 71 operating in unison. As the cable 130

79 is wound upon the drum 70, the telescopic pusher is moved into the coke oven, the forward end thereof being supported by the shoes 39 resting upon the bottom of the oven, while the rear end thereof is supported by the cross head 44 traveling upon the rails 20 of the revoluble frame. This is accomplished by the cable 79 being attached to the bearing 52 of the outer member, consequently 5 this member and the inner member thereof will be moved forward, until the bearing 46 of the inner member impinges the stop 58 of the revoluble frame; the outer member will then be carried forward, the wheels 42 10 of said outer member supporting the same upon the inner member. After the pusher head 34 has forced the coke from the oven into a suitable car at the opposite side of the oven, the motor 73 is reversed to wind the 15 cable 81 upon the drum 71. As the sheaves 29, 30 and 31 are carried by the revoluble frame, and the sheave 54 by the outer member of the pusher, this outer member will be drawn rearwardly upon the inner member 20 and then both members pulled rearward together upon the revoluble frame. This is 25 accomplished by locating the sheave 57 at the forward end of a revoluble frame. To swing the revoluble frame around whereby 30 an oven upon the opposite side can be operated upon, the operator manipulates the controller 67, which through the medium of the motor 59, worm 61, wheel 62, shaft 63, pinion 66, and rack 15, swings the frame 35 around into the desired position. As heretofore stated controller 75 is employed in connection with the motor 14 and the trolley 19 for moving the entire machine upon the rails 11.

40 It is thought that the utility and operation of the coke pushing machine will be fully understood from the foregoing description, and we reserve the right to make any such changes in the construction of the same as 45 fall within the scope of the appended claims.

Having now described our invention what we claim as new, is:—

1. A coke pushing machine embodying a movable carriage, a circular rack carried 50 thereby, a frame revolubly mounted upon said carriage, a superimposed platform carried by said frame, a telescopic pusher located upon said frame, said pusher comprising an inner member, an outer member mov- 55 ably mounted upon said inner member, a pusher head carried by the forward end of said outer member, a cross head carried by the rear end of said inner member and adapted to travel upon said frame, means for simultane- 60 ously moving said members and moving said outer member independent of said inner member, said means including sheaves, drums located upon said platform, cables connecting with said drums and passing over said sheaves, 65 and connecting with said frame and with

said outer member, a motor for operating said drums: means carried by said platform and engaging said rack for revolving said frame, and means located upon said platform for controlling the operation of said 70 motors and the movement of said carriage.

2. A coke pushing machine embodying a movable carriage, a circular rack carried thereby, a frame revolubly mounted upon said carriage, a superimposed platform carried by said frame, a telescopic pusher located upon said frame, said pusher comprising an inner member, an outer member mov- 75 ably mounted upon said inner member, a pusher head carried by the forward end of said outer member, a cross head carried by the rear end of said inner member and adapted to travel upon said frame, means for simultaneously moving said members and moving said outer member independent 80 of said inner member, said means including sheaves, drums located upon said platform, cables connecting with said drums and passing over said sheaves and connecting with said frame and with said outer member, a 85 motor for operating said drums; and means carried by said platform and engaging said rack for revolving said frame.

3. A coke pushing machine embodying a movable carriage, a circular rack carried 95 thereby, a frame revolubly mounted upon said carriage, a superimposed platform carried by said frame, a telescopic pusher located upon said frame, said pusher comprising an inner member, an outer member mov- 100 ably mounted upon said inner member, a pusher head carried by the forward end of said outer member, a cross head carried by the rear end of said inner member and adapted to travel upon said frame, means 105 for simultaneously moving said members and for moving said outer member independent of said inner member, said means including sheaves, drums located upon said platform, cables connecting with said drums 110 and passing over said sheaves and connecting said frame with said outer member, and a motor for operating said drums.

4. A coke pushing machine embodying a movable carriage, a circular rack carried 115 thereby, a frame revolubly mounted upon said carriage, a superimposed platform carried by said frame, a telescopic pusher located upon said frame, said pusher comprising an inner member, an outer member mov- 120 ably mounted upon said inner member, a pusher head carried by the forward end of said outer member, a cross head carried by the rear end of said inner member and adapted to travel upon said frame, and 125 means for simultaneously moving said members and for moving said outer member independent of said inner member.

5. A coke pushing machine embodying a carriage, a frame revolubly mounted upon 130

said carriage, a superimposed platform carried by said frame, a telescopic pusher located upon said frame, said pusher comprising an inner member, an outer member movably mounted upon said inner member, a pusher head carried by the forward end of said outer member, a cross head carried by the rear end of said inner member and adapted to travel upon said frame, means for simultaneously moving said members, and means for independently moving said outer member.

6. A coke pushing machine embodying a carriage, a frame revolvably mounted upon said carriage, a telescopic pusher located upon said frame, said pusher comprising an inner member, an outer member movably mounted upon said inner member, a pusher head carried by the forward end of said outer member, a cross head carried by the

rear end of said inner member and adapted to travel upon said frame, means for moving said members, and means for moving said revolvable frame.

7. A coke pushing machine embodying a carriage, a revolvable frame mounted thereon, a telescopic pusher located upon said frame, said pusher comprising two members movably connected together, a pusher head carried by the outer of said members, means for simultaneously moving said members, and means for moving one of said members independently of the other. 25 30
